UNITED STATES PATENT OFFICE.

RICHARD G. DUNWODY AND JOHN W. WILLS, OF ATLANTA, GEORGIA.

FABRIC AND PROCESS FOR MAKING THE SAME.

1,187,890.

Specification of Letters Patent. Patented June 20, 1916.

No Drawing.

Application filed April 19, 1916. Serial No. 92,219.

To all whom it may concern:

Be it known that we, RICHARD G. DUNWODY and JOHN W. WILLS, citizens of the United States, residing at Atlanta, in the county of Fulton and State of Georgia, have invented certain new and useful Improvements in Fabrics and Processes of Making the Same, of which the following is a specification.

10 This invention relates to an improved fabric and the process by which the same is made.

One of the objects of the present invention is to make a strong, durable fabric 15 which will be substantially waterproof.

Another object is to provide a simple and practical process for manufacturing material of the above character.

A further object is to provide an inexpensive process for making waterproof fabric which may also have any desired color or design.

Other objects will be in part obvious and in part hereinafter pointed out.

25 The invention accordingly consists in the several steps and in the relation of either or one or more of those steps to each of the others thereof, as well as to the material produced by such steps, as will be exemplified in the hereinafter disclosed process and the scope of the application of which will be indicated by the claims that follow.

In brief, the process may be said to consist of taking coarse raw cotton and treating the same to remove the natural oils and fats thereof, after which the cotton is treated and formed into sheets of the desired size and rendered waterproof by the addition or application of suitable materials. The mat thus formed may then be subjected to pressure and heat and have incorporated therewith coloring matter either throughout its entire area or in predetermined portions to make a suitable design.

45 In carrying out this process briefly outlined above, we prefer to first subject the coarse raw cotton to the action of a gasolene mixture which is found to be a suitable and inexpensive solvent for eradicating the 50 natural oils of the cotton. The cotton thus

treated is then run through a picker and formed into sheets of desired size, after which the mat so formed may be bleached if desired, although this step is not in any way essential, especially if the mat is to be subsequently colored. These sheets are then treated with a solution composed largely of collodion or the like and rosin, to which may be added rubber cement. The mats are thoroughly saturated with this solution and then dried, and pressed into thin sheets by being run through rollers under great pressure, and preferably at a relatively high temperature. Any form of roller may, of course, be used; but it is found that large electrically heated collars are more desirable. The fabric so manufactured may be dyed either before or after this pressing step by the addition of coloring pigments placed over its entire area, or in predetermined spots to produce a regular design thereon. The article so manufactured will be found to be strong, durable and inexpensive and capable of all uses where a coarse, strong woven fabric is now used.

75 As many changes could be made in carrying out the above process without departing from the scope of the invention, it is intended that all matter contained in the above description shall be interpreted as 80 illustrative and not in a limiting sense.

Having thus described our invention what we claim as new and desire to secure by Letters Patent is—

1. The herein described article of manufacture composed of raw cotton impregnated with a solution of collodion, rosin and rubber.

2. The herein described article of manufacture composed of raw cotton, collodion and rosin pressed together in thin flexible sheets.

3. The herein described process of making fabric which consists in removing the natural oils from the raw cotton by the use of gasolene, impregnating the fibers with a solution of collodion, rosin and rubber, drying the mixture and passing the same through heated rollers.

4. The herein described process of making

fabric which consists in removing the oils and fats from the raw cotton by the use of gasolene, picking the cotton and forming the same into sheets, impregnating the sheets with a solution of collodion and rosin, passing the sheets through heated rollers under great pressure, and adding a coloring matter thereto.

In testimony whereof we affix our signatures in presence of two witnesses.

RICHARD G. DUNWODY.
JOHN W. WILLS.

Witnesses:

T. C. CONWAY,
S. S. KING.
